BEET TOPPING MACHINE

John L. Braden, Burley, Idaho

Application April 27, 1940, Serial No. 332,107

12 Claims. (Cl. 55—107)

This invention relates to beet topping devices for cutting off the beet tops with the beets in the ground.

In the growing of beets, particularly the larger beets such as the sugar beets, it is well known that a portion of each beet projects above the ground, and as the beets vary in size, the projecting part of the beet will also vary. Various types of topping machines are in use which pass over the beets and cut the tops off. However, the machines now available are so constructed that the cutting blade or blades are supported from a mobile frame in such a manner that they are a definite and fixed distance off of the ground. Where the beets are irregular in size, the blade or blades must be set low enough to top the larger beets, and this results in the smaller beets having an excessive portion thereof cut off. This is due to the fact that the blade or blades move in a fixed horizontal plane. Any unevenness of the ground will also cause either an excess cutting of the beet top or else a failure to properly top the beets.

It is, therefore, an object of this invention to provide a beet topping machine which will cut off the desired amount of the beet top irrespective of the size of the beet, the amount cut off will vary from one quarter of an inch to an inch.

Another object of this invention is to provide a beet topping machine which is so constructed that the cutting mechanism is actuated by contact of the mechanism with the projecting portion of the beet.

A further object of this invention is to provide in a beet topping machine of this kind, a cutting mechanism which is adapted to cut off the top in a horizontal cutting operation and simultaneously split the severed top so that the severed top may be forced to the opposite sides of the row of beets, thus permitting the topped beets to be removed by a suitable plow or digging means without mixing the beets with the severed tops.

A still further object of this invention is to provide a topping mechanism which is swingably supported from a mobile frame and which is adapted to be vertically rocked by contact of the mechanism with the projecting portion of the beet so that the larger beets will effect a greater movement of the mechanism than the smaller beets, but the amount of the top cut off from the larger beets will be proportionately the same as is cut off from the smaller beets, thus effecting a very considerable saving of the beet.

A further object of this invention is to provide a beet topping mechanism wherein contact of the

mechanism with the beet will move the cutter to a set or operative position rearwardly of the beet and hold the cutter in its set position during the passage of the mechanism over the beet whereupon the cutter will be released for forward movement to a cutting position. 5

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed. 15

In the drawings:

Figure 1 is a fragmentary side elevation of a beet topping mechanism constructed according to an embodiment of this invention.

Figure 2 is a fragmentary vertical section taken longitudinally through the machine. 20

Figure 3 is a sectional view taken on the line 3—3 of Figure 2.

Figure 4 is a sectional view taken on the line 4—4 of Figure 2. 25

Figure 5 is an enlarged fragmentary sectional view taken longitudinally of the machine showing a portion of the controlling means for the beet topping mechanism in inoperative position.

Figure 6 is a sectional view taken on the line 6—6 of Figure 3.

Referring to the drawings, the numeral 10 designates generally a mobile frame structure which at the rear thereof is adapted to have a pair of wheels and supporting means therefor (not shown), and the frame 10 is also provided with a pair of forward wheels 11 which are mounted on a pair of downwardly extending supporting members 12 provided with spindles 13 on which the wheels 11 are rotatably mounted. A 40 draft bar 14 has its rear end portion thereof overlapping the forward end of the frame 10 and the forward end of the draft bar 14 is adapted to be connected to a tractor or is adapted to have a pair of horses connected to a tongue 15 which is secured by fastening devices 16 to the forward end of the draft bar structure 14. In practice there are two of the draft bars 14 which are disposed in spaced apart relation and the rear ends of the draft bars 14 are downwardly curved as at 50 17 and extend rearwardly of the forward end of the frame 10. A pair of connecting links 18 are pivotally secured as at 19 to the rear ends of the downwardly curved portion 17 and the forward ends of the links 18 are pivotally mounted as at 55

20 to a pair of upright supporting members 21 which are fixed to the forward end of the frame 10.

5 In operative position, which is the position shown in Figure 1, the rear end of the draft bar structure 14 is adapted to rest on the horizontal forward end of the frame 10. In this position, the pivot 19 is disposed below the pivot 20 so that a forward pull on the draft bars 14 will not raise 10 the links 18 and thus raise the beet topping mechanism to be hereinafter described.

A spring 21 is connected at one end to the pivot 19 and at the opposite or lower end is connected 15 to an eye bolt 22 which is fixed to the lower end of an L-shaped supporting member 23. The supporting member 23 has one side thereof substantially horizontal and secured beneath the forward upper end portion of the frame 10. The spring 21 yieldably urges the rear ends of the 20 bars 14 downwardly.

A beet topping mechanism generally designated 25 as 24 is disposed below the draft bars 14 and forwardly of the frame 10. The beet topping mechanism 24 comprises a pair of spaced apart parallel bars 25 which are inclined to the vertical and the forward upper ends of the bars 25 are laterally offset as at 26. The forward ends of the bars 25 are pivotally mounted on a pivot member 27 which extends through a pair of depending 30 supports 28 which are fixed to and depend from the two bars 14 closely adjacent the draft tongue 15. The supporting members 28 are secured one to each draft bar 14 by fastening devices 29. A pair of parallel frame bars 30 are disposed in 35 spaced relation to the supporting bars 25 and the forward upper ends of the bars 30 are bent inwardly as at 31 and then continued forwardly as at 32. The inwardly and obtusely bent portions 31 of the bars 30 form a V at the upper ends 40 of the bars 30 and the straight portions 32 are secured as by fastening devices 33 to the supporting bars 25.

A roller shaft 34 extends through an outer side bar 30 and an inner bar 25, and a roller 35 is 45 rotatably mounted on each shaft 34. A vertically disposed bar 36 extends upwardly from the lower end of each bar 25 and may be formed integral with a bar 25. The two vertical bars 36 have secured therebetween an upwardly extending link 50 37 which at its lower end is secured as by a pivot member 38 to the upper ends of the two bars 36. The link 37 is provided with a plurality of holes 39 and one leg 40 of a bell crank 41 is pivotally secured as by a pivot member 42 in a selected hole 39. The bell crank 41 is pivotally mounted 55 on a shaft 43 extending between the two bars 14 and the upper leg 44 of the bell crank 41 is provided with a hole 45 in which one end of a spring 46 engages. The spring 46 is connected at the 60 opposite end thereof to an eye bolt 47 which extends through a vertically disposed support 48 which is carried by the rear portions of the draft bars 14.

The spring 46 provides a balancing or tensionable means for yieldably holding the topping mechanism 24 in the desired operative position beneath the draft bars 14. A stop member 49 extends between the two draft bars 14 and the upper leg or side 44 of the bell crank 41 is adapted 70 to engage against the stop member 49.

A shield comprising a plate 50 is disposed beneath the frame members or bars 25 and 30 and this plate 50 is provided with upturned marginal portions 51 engaging against the outer sides of 75 the side bars 30 and is also provided with up-

turned forward end portions 52 engaging the convergent portions 51 of the side members 30. The shield or plate structure 50 is detachably secured as by a single bolt 53 to the two supporting bars 25, the bolt 53 engaging between the two bars 25 upwardly from the lower ends thereof. A stationary top splitting blade or cutter 54 is secured as by a pivot member 55 between the two supporting bars 25. The blade 54 is provided with an arcuate slot 56 downwardly from the 10 pivot member 55 and a blade clamping bolt 57 extends through the two bars 25 and the slot 56 and holds the blade 54 in adjusted position relative to the plate or shield 50.

The lower end of the plate 50 as shown in Figure 2 is preferably upturned as at 58 and provides a means whereby the surface of the two rollers 35 may be constantly cleaned as the device is moving over the surface of the ground. The shield 50 is provided with an elongated slot 59 through which the blade 54 projects. The rear portion of the blade 54 extends below the two rollers 35 as shown in Figures 1 and 2 and is adapted to engage the top of the beet so as to divide the beet top in order that the cutting 25 mechanism to be hereinafter described may operate to move the split portions of the beet top laterally of the row of beets.

A cutter carrying plate 60 is slidably disposed 30 between one of the frame bars 25 and the stationary cutter 54 and the plate 60 at its forward end has secured thereto an upwardly extending arm 61 which has fixed to its upper end a pair of coupling members 62. The coupling members 62 are fixed to the upper end of the arm 61 by a bolt or pivotal member 63. Preferably the two coupling members 62 are provided with outwardly offset upper portions 64 having an opening 65 in which the lower end of a blade tensioning spring 66 is adapted to engage. The spring 66 not only tensions the movement of the plate 60 but also serves as a yieldable operator for the beet topping and splitting blades which are carried by the plate 60. The upper ends of the two blade operating springs 66 engage in an opening 67 which is formed in a supporting member 28. A vertically disposed beet top splitting blade 68 is carried by the plate 60 and is disposed in face abutting relation to the stationary blade 54 and contacts with this blade 54 in splitting the top of the beet. The blade 68 moves downwardly and rearwardly to an operative or set position when the roller 35 rides upwardly over the beet and when the roller drops off of the beet the blade 68 moves forwardly and upwardly to a cutting position 55 which is the position shown in Figures 1 and 2.

A V-shaped beet topping blade 69 is disposed in a horizontal position beneath the plate 60, being fixed thereto by any suitable fastening means and the convergent end of the blade 69 is foremost and merges in the rear end of the splitting blade 68 extending rearwardly from the two rollers 35 and the apex of the blade 69 is disposed substantially centrally in the space between the two rollers 35.

An elongated lever 70 which is provided with an obtusely disposed forward end portion 71 is pivotally mounted on the pivot 27. The lever 70 is connected to the blade carrier 60 by means 70 of a pair of links 72. The links 72 are pivotally secured as at 73 to the blade carrier 60 and the links 72 are provided with a plurality of holes 74 through selected ones of which a bolt or pivot member 75 is adapted to engage. The lever 75

70 is also provided with a plurality of holes 76 through a selected one of which a bolt or pivot member 75 is adapted to engage so as to adjust the position of the lower portion of the lever 70 with respect to the blade carrier 60. A link 77 is pivotally mounted at one end on a pivot 78 engaging through a selected opening 74 in each link 72 and the link 77 is also provided with a plurality of spaced openings 78a through which a pivot member 79 is adapted to engage for adjustably and pivotally securing the link 77 between the two upright bars 36. A pair of links 80 are pivotally secured on a pivot member 83 which engages through the forward upper end of the arm 61 which is connected to the blade carrier 60 and the two links 80 are provided with spaced openings 82 through selected ones of which a pivot member 83 is adapted to engage. The pivot 83 also engages through a selected opening 84 formed in the lever 70. There are a number of these openings 84 in the lever 70 so that the links 80 may be adjusted relative to the lever 84.

25 A blade operating lever 85 is pivotally secured on a pivot member 86 extending between the depending supporting members 28 and above the lever 70. The lever 85 is provided with an obtusely disposed rear lower end 87 which has formed therein a plurality of spaced apart openings 88. A link 89 is mounted at one end on a pivot 90 engaging through the rear end of the lever 70 and the link 89 extends upwardly and forwardly of the lever 70 and is pivotally secured on a pivot member 91 engaging through a selected opening 88. A link 92 is pivotally mounted at its upper end on the pivot member 91 and the link 92 is provided with a plurality of openings 93 formed therein through which a pivot member 94 engages. The pivot member 94 engages through the two supporting members 36 and the link 92 coacts with the link 89 and levers 70 and 85 in effecting the desired movement of the blade carrier 60 with respect to the frame structure comprising the bars 25 and the two side bars 30.

The topping mechanism hereinbefore described is raised to an inoperative position or lowered to an operative position by means of a rock lever or handle 95 which is pivotally mounted on a shaft 96 engaging through upstanding ears 97 carried by a supporting bar or member 98 which is fixed to the frame 10 rearwardly of the wheels 11. A toothed quadrant 99 extends upwardly from the supporting member 98 and the lever or operator 95 is provided with a spring pressed latching dog 100 which is operated from a bell crank lever 101 pivotally carried by the upper portion of the lever 95. The lever 95 is provided with an upwardly curved lifting and lowering arm 102 which is formed integral therewith and the upturned forward end of the arm 102 is connected to the downwardly curved rear end portions 17 of the draft bars 14 by means of a pair of links 103 which are mounted on the shaft or pivot member 98 and also a second pair of links 104 which are pivotally connected as by a pivot member 105 to the upper ends of the link or links 103. The links 104 are pivotally connected as by a pivot member 106 to the upturned forward end of the arm 102.

In order to provide a means whereby the wheels 11 may be raised off of the ground when the topping mechanism is raised by means of the lever 95, I have provided a bell crank 107 which

is pivotally mounted on a pivot member 108 engaging a pair of supporting bars 108a which are fixed to the draft bars 14. One end of the bell crank 107 is connected to a lifting rod 109 which is slidable through an extension 110 carried by the L-shaped member 23. The rod 109 is provided with a head 111 disposed below the extension 110 and when the lever 95 is rocked rearwardly so as to raise the rear end portions 17 of the bars 14, the lifting rod 109 will be raised until the head 111 engages the extension 110. The extension 110 is provided with an opening 112 through which the rod 109 slidably engages.

A lifting lever 113 is rockably mounted on a pivot 114 engaging through the supporting members 48 and the lever 113 is connected to the bell crank 107 by means of a link 115. The link 115 is pivotally connected at one end to the rear end of the bell crank 107 by means of a pivot 116 and the rear end of the link 115 is pivotally secured to the lever 113 upwardly and rearwardly of the pivot 114 by means of a pivot 117. When the lifting lever 113 is in the position shown in Figure 1, this lever is locked against rocking movement on the pivot 114 and in this position the rear ends of the draft bars 14 cannot be raised beyond the limit permitted by the head 111 of the lifting rod 109. If it is desired to raise the rear ends of the draft bars 14 to an extent greater than that permitted by the stop or head 111, the lever 113 must be raised so that the pivot 117 will be disposed above the pivot 114. When the lever 113 is raised so as to position the pivot 117 above the pivot 114, the lever 95 can be rocked downwardly to the limit permitted by the quadrant 99 and the additional raising of the draft bars 14 relative to the frame 10 will cause the bell crank 107 to rock on the pivot 108 and at this time the frame 10 will be in a substantially horizontal position with the wheels 11 engaging the ground and the draft bars 14 will be inclined to the horizontal with the rear ends thereof uppermost and in substantially the position shown in Figure 5.

If it is desired to raise the wheels 11 off of the ground and also raise a pair of downwardly convergent plows or beet digging members 118 out of the ground, the lever 113 is rocked downwardly and rearwardly to the position shown in Figure 5. This will raise the forward end of the frame 10 to the position shown in Figure 5 and thus raise the wheels 11 off of the ground and also move the plow members 118 to an inoperative position. The plow members 118 are of conventional construction and are mounted on plow supporting members 119 which are fixed by fastening devices 120 to the frame 10 rearwardly of the wheels 11.

A bracing bar 121 is connected at one end to a supporting bar 119 and at the other or forward end is fixed by a fastening device 122 to the frame 110. It will be understood that a pair of wheels are pivotally mounted on the frame 10 rearwardly of the plows 118 and the supporting bars 119.

In order to provide a means whereby the trash or split tops may be forced laterally of the digging plows 118, I have provided a pair of depending and downwardly directed rods 123 which are secured at their upper ends in adjusted position to the draft bars 14 by means of a pair of clamping bars 124 which are adapted to be bolted by bolts 125 to the bars 14 forwardly of the frame 10. The bars 123 extend downwardly between the two wheels 11 and each bar 123 is

provided with an upwardly curved lower end 126 which if desired may engage the surface of the ground when the topping mechanism 24 is in an operative position so as to engage the split 5 and cut tops and force these tops laterally of the digging members 118. The upwardly curved lower ends 126 of the rods 123 may be disposed in rearwardly divergent position so as to force the trash and split and severed tops away from 10 the digging or lifting plows 118.

In the use and operation of this beet topping mechanism, the draft bars 14 are adapted to be connected to a suitable pulling device or may be connected to a pair of horses and the topping 15 mechanism 23 is lowered to an operative position by raising the lever 95 to the desired position. The raising of the lever 95 will drop the rear ends 20 of the draft bars 14 until they are positioned in the desired relation with respect to the frame 10. In their lowermost position, the draft bars 14 may rest on top of the forward end of the frame 10 as shown in Figure 1 and in this position the draft bars 14 will be substantially horizontal. The device is then pulled along the row of beets 25 and as each beet B as shown in Figure 1 has a portion thereof projecting above the top of the ground, the rollers 35 will ride over the projecting portion of the beet B and raise the frame members 25 and 30 together with the shield 50 30 and the beet top splitting and cutting mechanism.

The stationary plate 54 will move through the beet top and effect at least a partial splitting of the top and as the rollers 35 ride upwardly and over the projecting portion beet B, the blade 35 carrier 60 will be shifted rearwardly. This rearward shifting of the blade carrier 60 is effected by means of the linkage 72 and 80 and the lever 70. As the blade carrier 60 moves rearwardly, the top splitting blade 68 and the topping blade 40 69 will move with the carrier 60 against the tension of the springs 66. After the rollers 35 pass over the top of the beet B, the carrier 60 is released and the springs 66 will snap the two blades 68 and 69 forwardly so as to split the top 45 of the beet B and at the same time make a horizontal cut completely through the top of the beet B.

The linkage 89, 92 and the rock lever 85 also assist in effecting the desired rearward movement 50 of the blade carrier 60 as this carrier is shifted upwardly with the upward movement of the rollers 35 and the frame structure comprising the frame bars 25 and 30.

With a beet topping mechanism of this kind, 55 the mechanism 24 may be adjusted to the desired position relative to the ground and to the smallest beets which it may be desired to top. As the device is moved over the ground and the rollers 35 engage the projecting portions of the beets, 60 the rollers 35 will ride over these beets and with a mechanism of this kind, different sizes of beets will have the tops thereof cut off at different heights from the ground so that the topping mechanism hereinbefore described will not cut 65 off an undue amount of the body of the beet where a larger beet is encountered as is the case with beet topping mechanisms at present available and which are not automatically shifted by contact with the beets.

70 After the beet tops have been cut off and split, the digging plows 118 which follow the topping mechanism will lift the topped beets out of the ground and dispose the beets in a row on top of the ground.

75 A beet topping mechanism has been con-

structed according to an embodiment of this invention and placed in actual operation and has been found to provide a more satisfactory topping mechanism than one which moves in a horizontal plane over the ground and which must be set for a maximum depth. The beet topping mechanism hereinbefore described will effect a considerable saving in the amount of beet which is cut off in the topping operation as the device can be readily adjusted as to tension by means of the tensioning spring 46 which yieldably holds the topping mechanism in a position for engagement with the tops of the beets. As the beet mechanism 24 rises, the bell crank 41 will be rocked on the pivot 43 against the tension of the spring 46 so that this tension may be adjusted to the desired degree in order to hold the rollers 35 of the topping mechanism in a position for engagement with the tops of the beets.

What I claim is:

1. A beet topping device comprising a mobile frame structure, a topping blade carrier disposed below said structure, a swingable supporting means for said carrier, means connected to said carrier and said supporting means for effecting movement of said carrier lengthwise of said supporting means simultaneous with vertical movement of said supporting means, means for adjusting said connecting means for varying the movement of the carrier relative to said supporting means, a beet topping blade carried by said carrier, and means for elevating or lowering said supporting means.

2. A beet topping device comprising a beet topping blade, vertically swingable supporting means for said blade, means carried by said supporting means engageable with a beet for vertically swinging said supporting means, means active upon upward movement of said supporting means for shifting said blade rearwardly of said supporting means, and means active when said first means has moved out of engagement with a beet for moving said blade forwardly to a cutting position.

3. A beet actuated topping mechanism comprising a beet topping blade, a vertically swingable support for said blade, yieldable means constantly urging said blade forwardly relative to said support, and means active upon upward movement of said support for moving said blade rearwardly relative to said support.

4. A beet actuated topping mechanism comprising a beet topping blade, a beet top splitting blade extending forwardly of said topping blade and fixed relative thereto, a vertically swingable support for said blades, yieldable means constantly urging said blades forwardly relative to said support, and means active upon upward movement of said support for moving said blades rearwardly relative to said support.

5. A beet actuated topping mechanism comprising a beet topping blade, a beet top splitting blade extending forwardly of said topping blade and fixed relative thereto, said top splitting blade having a portion thereof projecting below said topping blade, a swingable support for said blades, a second beet top splitting blade fixed relative to said support and disposed in face abutting relation to said first top splitting blade, means constantly urging said topping blade and said first splitting blade forwardly relative to said support, and means active upon upward movement of said support for moving said topping blade and said first splitting blade relative to said support.

20

35

45

50

6. A beet actuated topping mechanism comprising a beet topping blade, a beet top splitting blade extending forwardly of said topping blade and fixed relative thereto, said top splitting blade having a portion thereof projecting below said topping blade, a swingable support for said blades, a second beet top splitting blade fixed relative to said support and disposed in face abutting relation to said first top splitting blade, means constantly urging said topping blade and said first splitting blade forwardly relative to said support, means active upon upward movement of said support for moving said topping blade and said first splitting blade relative to said support, a mobile frame, and means engaging said frame and said support for elevating or lowering said support relative to said frame.

7. A beet actuated topping mechanism comprising a beet topping blade, a beet top splitting blade extending forwardly of said topping blade and fixed relative thereto, said top splitting blade having a portion thereof projecting below said topping blade, a swingable support for said blades, a second beet top splitting blade fixed relative to said support and disposed in face abutting relation to said first top splitting blade, means constantly urging said topping blade and said first splitting blade forwardly relative to said support, means active upon upward movement of said support for moving said topping blade and said first splitting blades relative to said support, a mobile frame, means engaging said frame and said support for elevating or lowering said support relative to said frame, and tensionable means constantly urging said support downwardly.

8. A beet actuated topping mechanism comprising a beet topping blade, a beet top splitting blade extending forwardly of said topping blade and fixed relative thereto, said top splitting blade having a portion thereof projecting below said topping blade, a swingable support for said blades, a second beet top splitting blade fixed relative to said support and disposed in face abutting relation to said first top splitting blade, means constantly urging said topping blade and said first splitting blade forwardly relative to said support, means active upon upward movement of said support for moving said topping blade and said first splitting blades relative to said support, a mobile frame structure including a wheeled frame and a draft structure, link means connecting the draft structure to said wheeled frame, and means carried by said wheeled frame for simultaneously elevating said support and the rear portion of said draft structure.

9. A beet actuated topping mechanism comprising a beet topping blade, a beet top splitting blade extending forwardly of said topping blade and fixed relative thereto, said top splitting blade having a portion thereof projecting below said topping blade, a swingable support for said blades, a second beet top splitting blade fixed relative to said support and disposed in face abutting relation to said first top splitting blade, means constantly urging said topping blade and said first splitting blade forwardly relative to said support, means active upon upward movement of said support for moving said topping blade and said first splitting blades relative to

said support, a mobile frame structure including a wheeled frame and a draft structure, link means connecting the draft structure to said wheeled frame, means carried by said wheeled frame for simultaneously elevating said support and the rear portion of said draft structure, and means engaging said draft structure and said wheeled frame for elevating the forward portion of said wheeled frame when the rear portion of said draft structure is in elevated position.

10. A beet actuated topping mechanism comprising a mobile frame, a supporting member below said frame, means swingably supporting said member from said frame, a blade carrier movably carried by said supporting member, means constantly urging said carrier in one direction, means carried by said supporting member and engaging said carrier for moving said carrier in the opposite direction upon upward swinging of said supporting member, means for adjusting said carrier moving means for varying the movement of the carrier in the said opposite direction upon upward swinging of said supporting member, a topping blade carried by said carrier, and rollers carried by said supporting member forwardly of said topping blade for engagement with a beet to thereby vertically move said supporting member upon contact of said rollers with a beet.

11. A beet actuated topping mechanism comprising a mobile frame, a supporting member below said frame, means swingably supporting said member from said frame, a blade carrier movably carried by said supporting members, means constantly urging said carrier in one direction, means carried by said supporting member and engaging said carrier for moving said carrier in the opposite direction upon upward swinging of said supporting member, a topping blade carried by said carrier, a top splitting blade carried by said supporting member and projecting downwardly therefrom, a second top splitting blade carried by said carrier and disposed in face abutting and operative relation to said first top splitting blade, and rollers carried by said supporting member forwardly of said topping blade for engagement with a beet to thereby vertically move said supporting member upon contact of said rollers with a beet.

12. A beet actuated topping mechanism comprising a mobile frame, a supporting member below said frame, an upwardly extending suspension means carried by said supporting member, a bell crank rockably carried by said frame, means pivotally connecting one leg of said bell crank to said suspension means, tensionable means connected to the other leg of said bell crank and to said frame, a blade carrier movably carried by said supporting member, means constantly urging said carrier in one direction, means carried by said supporting member and engaging said carrier for moving said carrier in the opposite direction upon upward swinging of said supporting member, a topping blade carried by said carrier, and rollers carried by said supporting member forwardly of said topping blade for engagement with a beet to thereby vertically move said supporting member upon contact of said rollers with a beet.
